UNITED STATES PATENT OFFICE.

LESLIE S. HACKNEY, OF ST. PAUL, MINNESOTA.

ROADWAY FOR AUTOMOBILES.

No. 870,775.

Specification of Letters Patent.

Patented Nov. 12, 1907.

Application filed November 2, 1906. Serial No. 341,779.

To all whom it may concern:

Be it known that I, LESLIE S. HACKNEY, of St. Paul, Ramsey county, Minnesota, have invented certain new and useful Improvements in Roadways for Automobiles, of which the following is a specification.

The object of my invention is to provide a roadway or track for automobiles which will be of simple and comparatively inexpensive construction and will enable a car to be driven at any desired speed over country roads regardless of the weather or the condition of the road.

My invention consists generally in providing a track for the wheels, raised if preferred above the level of the roadway and having concave upper surfaces wherein the wheels will roll easily and without any tendency to sidewise or lateral movement.

In the accompanying drawings, forming part of this specification, Figure 1 is a transverse sectional view of a roadway embodying my invention. Fig. 2 is a similar view showing a modified construction. Fig. 3 is also a transverse sectional view showing another form of track or tread for the wheels.

In the drawing, 2 represents a gravel roadway the surface of which may be oiled if preferred to prevent dust, and 3 represents blocks, preferably of concrete forming a foundation or base embedded on each side of the roadway in the gravel and held securely thereby and forming a substantial support for the tile 4 placed thereon. These tile are arranged end to end and form 30 when the roadway is completed, a continuous track on which the automobile may travel at a high speed regardless of the character of the country through which it may be running. The tile preferably, have broad bases 5 that are sunk into the top of the foundation blocks 3, as indicated in Fig. 1, and the walls of the tile preferably are tapered or inclined toward one another from the base toward the top and an inwardly inclined ridge 6 is preferably formed, extending lengthwise of each tile on its outer wall, making its upper surface a little higher on the outside and tending to guide or direct the wheels of the automobile toward the inner side of the track, thus greatly reducing the danger of the car running off the way. These tile may be made of any suitable length and braced lengthwise 45 by a web or wall 7 adapted to support the middle portion of the tread while the inward taper of the side walls cause them to act as braces for the upper portion of the tile.

I propose to provide a dove-tail track to allow cars to

travel in both directions without the necessity of providing crossing points.

In Fig. 2 a modified construction is shown which consists in providing a foundation 8 of concrete embedded in the roadway a suitable distance and having a concave upper surface 9 in which the wheels travel. 55 The opposite foundation blocks are bonded or tied together by means of rods 10 extending transversely of the roadway and having their ends embedded in the blocks 8 and anchored therein by means of upwardly turned points 11. This form of roadway, as it dispenses with the use of the hollow tile will be a little cheaper to construct and probably will be found fully as durable and answer the purpose as well, except perhaps where the roadway is rough or the soil muddy or very sandy. In such cases a raised track such as is 60 shown in Fig. 1 would be more desirable. The upper surface of the blocks 8 as shown in Fig. 2, is curved so that the wheels of the car will have a tendency to run in the center of the block, it only being necessary for the driver to operate his steering apparatus on the 65 curves.

In Fig. 3 I have shown another modification which consists in providing tile 12 semi-circular in cross section substantially, and embedded in the roadway, the upper edges of the tile being substantially on a level 75 with the top of the way. The wheels travel in these tile and will be guided thereby even on the curves. This construction will probably be found even less expensive than the modification shown in Fig. 2.

A track of this kind can be built across long stretches 80 of sandy or muddy country at a comparatively small expense and enable automobiles to be run from one town to another over roads which without a track of this kind would be impassable.

I claim as my invention:

1. An automobile track comprising a roadway, a wheel track laid therein and composed of a series of foundation blocks and hollow tile blocks supported thereon and said tile blocks having concave surfaces whereon the wheels roll, substantially as described.

2. A track for automobiles comprising a roadway, foundation blocks embedded in said roadway, tile blocks mounted on said foundation blocks and having concave upper surfaces raised above the level of said roadway, the outer edges of said tile blocks forming guides for the 95 wheels, substantially as described.

3. An automobile track comprising a roadway, a series of concrete blocks embedded therein on each side of said roadway, hollow tile tapered from the base toward the top and having their lower portions embedded in the top 100

of said foundation blocks, and the outer edges of the tops of said tile being raised above their inner portions, to form guides for the wheels, substantially as described.

4. A track comprising a roadway, a series of foundation blocks embedded therein, hollow tile having their lower portions embedded in the top of said foundation blocks, and the outer edges of the tops of said tile being raised above their inner portions to form guides for the wheels.

5. A track comprising a roadway, foundations laid 10 therein in parallel rows, and blocks composed of hollow

tile mounted on said foundations to form a continuous track, the upper portions of said blocks being raised above the level of the roadway and forming a wheel track, substantially as described.

In witness whereof, I have hereunto set my hand this 15
29th day of October 1906.

LESLIE S. HACKNEY.
